(57) **CLAIM**

I claim the ornamental design for a hat organizing and displaying device, as shown and described.

DESCRIPTION

FIG. 1 is a perspective view of a hat organizing and displaying device, showing my design;

FIG. 2 is a front view;

FIG. 3 is a left side view;

FIG. 4 is a rear view;

FIG. 5 is right side view;

FIG. 6 is a top view; and,

FIG. 7 is a bottom view.

The broken line portion of the figure drawings is included to show portions of the article that form no part of the claimed design.
